UNITED STATES PATENT OFFICE.

WILLIAM J. NESBITT, OF LOS ANGELES, CALIFORNIA.

HEEL-CUTTING APPARATUS.

1,239,209.

Specification of Letters Patent.

Patented Sept. 4, 1917.

Application filed January 11, 1917. Serial No. 141,894.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to heel cutting apparatus; more particularly to a modified form of the apparatus which is disclosed in my application filed Nov. 20, 1916, Ser. No. 132,486.

One object of the invention is to provide a modified form of heel cutting apparatus consisting of a novel and improved construction, arrangement, and combination of parts and devices.

Further objects of the invention are to provide a novel and improved heel cutting apparatus which is comparatively simple in construction, economical to manufacture, compact and light in weight, easy and convenient to operate, and effective in use.

Other objects and the advantages of the invention will be apparent to those skilled in the art from a careful consideration of the following description of the preferred construction embodying the invention, taken in connection with the accompanying drawings in which

Figure 1 is a side elevational view of the modified heel cutting apparatus; Fig. 2 is an enlarged broken sectional view taken on the line 2—2 of Fig. 1; Fig. 3 is a cross sectional view taken on the line 3—3 of Fig. 2; Fig. 4 is a broken sectional view taken on the line 4—4 of Fig. 1; Fig. 5 is an enlarged side elevational view of a portion of the apparatus; Fig. 6 is a broken sectional view taken on the line 6—6 of Fig. 5; Fig. 7 is an enlarged plan view of a portion of the apparatus; Fig. 8 is an enlarged broken side elevational view of one of the heel holding jaws; and Fig. 9 is a plan view of the same.

The supporting frame 10 has thereon the forwardly extending arm 11 to which is secured the stationary horizontal shaft 12. A sleeve 13 is slidably fitted on the shaft 12 and it is provided with an annular groove 14 in which is fitted the ring 15 which latter has thereon the projections or pins 16 which

are fitted in the slots 17 of the split ring 18 which has on its forward end the extension 19 and has on its rear end the extension 20 which latter is connected by the pivot 21 to the projection 22 on the arm 11. The extension 19 is provided with the handle 23. A latch 24 is mounted on the pivot 25 between the ears 26 on the extension 19, and it is provided with teeth adapted to engage the teeth 27 on the arcuate rack 28 which is suitably mounted on the arm 11. A spring 29 is adapted to normally hold the latch 24 in engagement with the teeth 27 to thereby lock the sleeve 13 in adjusted position.

On the sleeve 13 is mounted to swing in a vertical plane the arm 30 which at its upper end is provided with the socket 31 in which is pivotally fitted the part 32 which carries the pivot 33 on which is tiltably mounted the bar 34 which carries the heel gripping device.

On the sleeve 13 is mounted to swing in a vertical plane the arm 30 which at its upper end is provided with the socket 31 in which is pivotally fitted the part 32 which carries the pivot 33 on which is tiltably mounted the bar 34 which carries the heel gripping device. The heel gripping device comprises the lower plate 35 and the upper plate 36 which plates are disposed in substantially the same vertical plane and have the adjacent edge portions 37 thereof curved and adapted to fit in the crease between the heel seat and the heel of the shoe 38. The lower plate 35 is stationary, it being secured to the bar 34 by the screws 39 in this instance, and the upper plate 36 is secured by the screws 39' to the angular arm 40 which latter has thereon the pivot 41 which bears in the upper part of the rearward and upward extension 42 on the bar 34. The forward part of the edge portion 37 on one or both of the plates 35 and 36 is formed with teeth 43 adapted to hold and prevent forward movement of the shoe when the heel is moved against a cutter. The plate 36 may be provided on the side thereof with the auxiliary plate 44 which is secured to the plate 36 by the screws 39' and is provided with the teeth 45 which are adapted to engage the heel of the shoe 38 and prevent movement of the heel when it is moved against the cutter. The portion of the auxiliary plate 44 with the teeth 45 thereon is offset or spaced from the plate 36 so that the operator has an unobstructed view when placing the plate 36 in the crease of the shoe 38. The teeth 45 terminate short of the edge of the edge portion 37 so as not to prevent the edge portion 37 from extending into the crease of the shoe 38. The plate 110

35 may also have on the side thereof an auxiliary plate 44' which is secured by the screws 39 and is similar to the auxiliary plate 44 already described. A washer 45' is 5 disposed at one side of the extension 42 on the pivot 41, and a spacing washer 46' is disposed on said pivot between the extension 42 and the arm 40.

The arm 40 is connected to the part 32 by 10 the spring 46, and said arm 40 has at its lower end a curved lateral extension 47 in contact with the curved upper end 48 of the angular lever 49 which latter is pivotally mounted on the sleeve 13. An operating handle 50 may be connected to the angular lever 49, or a foot lever 51 mounted on the pivot 52 on the frame 10 may be pivotally connected to the rod 53 which latter is provided with the knuckle joints 54 and 55. A 15 spring 56 is suitably connected between the frame 10 and the lever 51, and another spring 57 which is stronger than the spring 56 is suitably connected between the frame 10 and the abutment 58, which latter is 20 mounted on the pivot 52 and bears against the underside of the lever 51. A shoulder 59 on the abutment 58 normally contacts with the stop 60 on the frame 10 to limit the upward movement of the abutment 58.

30 The cutter 61 preferably consists of a bandsaw which passes around the pulleys 62 and 63 which are mounted on the shafts 64 and 65 which latter are journaled in suitable bearings 66 and 67 on the frame 10. 35 A suitable device indicated at 68 is mounted on the frame 10 to guide and prevent displacement of the bandsaw 61. As shown, the shaft 65 may be driven by the electric motor 69 which has on its shaft 70 the spur pinion 71 in mesh with the spur wheel 72 on the shaft 65. The bar 34 which carries the shoe gripping device can be locked in adjusted position on the part 32 by turning the winged set-screw 73 which is mounted on 40 the part 32 and adapted to frictionally engage the lug 74 which is provided on the underside of the bar 34 and mounted on the pivot 33. A winged set screw 75 on the arm 30 can be turned to engage the part 32 and 45 lock the latter in adjusted position in the socket 31.

From the foregoing the construction, manner of use, and advantages of the invention will be apparent to those skilled in the art. 55 It will be seen that when the heel of the shoe 38 is placed in position on the stationary plate 35, the handle 23 may be operated to move the sleeve 13 transversely on the shaft 12 and in consequence move the heel transversely to the cutter 61 according to the amount that is to be cut off of the heel. If 60 it is desired to make an angular cut longitudinally of the heel the set screw 75 is loosened and then the part 32 is turned to 65 turn the heel according to the angle required

whereupon the part 32 is locked in adjusted position by tightening the set-screw 75. If it is desired to make an angular cut transversely of the heel, the set-screw 73 is loosened and then the bar 34 is turned on the pivot 33 to tilt the heel transversely to the cutter 61 so that the latter will cut the heel to have either side of the heel thicker than the other side. By pulling up on the handle 50 or by pressing down on the lever 51 the angular lever 49 and the angular arm 40 are moved to cause the plates 35 and 36 to grip the shoe 38 and to have the auxiliary plates 44 and 44' engage the heel of the shoe, whereupon further pressure on the lever 51 results in moving the heel in a curved path so that the heel is cut by the cutter 61.

The construction which has been particularly illustrated and described admits of changes and modifications—wherefore the right is reserved to all such changes and modifications as do not depart from the spirit and scope of the invention which is defined in the appended claims.

I claim:

1. Heel cutting apparatus comprising the combination of a substantially horizontal shaft, an arm adjustably mounted on said shaft and provided with a socket, a part adjustably fitted in said socket, and a shoe gripping device adjustably mounted on said part.

2. Heel cutting apparatus comprising the combination of a shaft, an arm having one end thereof adjustably mounted on said shaft and having a socket at its other end, a part adjustably fitted in said socket, a pivot on said part, and a shoe gripping device mounted on said pivot.

3. Heel cutting apparatus comprising the combination of a shaft, a sleeve slidably fitted on said shaft, an arm pivotally mounted on the sleeve and provided with a socket, a part adjustably fitted in said socket, and a shoe gripping device adjustably mounted on said part.

4. Heel cutting apparatus comprising the combination of a shaft, a sleeve adjustably mounted on said shaft, an arm having a socket at one end thereof and having its other end pivotally connected to said sleeve, a part adjustably fitted in said socket, a pivot on said part, and a shoe gripping device mounted on said pivot.

5. Heel cutting apparatus comprising the combination of a shaft, a sleeve adjustably mounted on said shaft, an arm pivotally mounted on said sleeve, a part adjustably mounted on said arm, a shoe gripping device adjustably mounted on said part and including a movable angular arm, and an angular lever in contact with said angular arm and pivotally mounted on said sleeve.

6. Heel cutting apparatus comprising the combination of a substantially horizontal

shaft, a sleeve slidably fitted on said shaft, an arm having a socket at one end thereof and having its other end pivotally mounted on said shaft, a part rotatably fitted in said socket, a pivot on said part, a shoe gripping device mounted on said pivot and including an angular arm, and an angular lever in con-

tact with said angular arm and pivotally mounted on said sleeve.

In testimony whereof I have signed my 10 name to this specification at Los Angeles, county of Los Angeles, State of California, this 4th day of January, A. D. 1917.

WILLIAM J. NESBITT.
